(57) **CLAIM**

The ornamental design for a wireless computer communicator, as shown and described.

DESCRIPTION

FIG. 1 is a top plan view of a wireless computer communicator showing my novel design;

FIG. 2 is a bottom plan view thereof;

FIG. 3 is a left side view thereof;

FIG. 4 is a right side view thereof; and

FIG. 5 is a front elevational view thereof;

FIG. 6 is a rear elevational view thereof; and

FIG. 7 is a perspective view of a wireless computer communicator of the present invention.
